UNITED STATES PATENT OFFICE.

SAMUEL B. SMITH, OF CLEVELAND, OHIO, ASSIGNOR TO THE BUCKEYE INCUBATOR COMPANY, OF SPRINGFIELD, OHIO, A CORPORATION OF OHIO.

INCUBATOR.

Application filed October 23, 1922. Serial No. 596,253.

To all whom it may concern:

Be it known that I, SAMUEL B. SMITH, a citizen of the United States, residing at Cleveland, in the county of Cuyahoga and 5 State of Ohio, have invented certain new and useful Improvements in Incubators, of which the following is a specification.

My invention relates to improvements in incubators and it relates more particularly 10 to incubators of large size in which the trays for the eggs are arranged in series one over the other and mounted for simultaneous tilting.

In this type of incubator the location of 15 the trays in the row are changed at intervals so as to gradually bring the eggs in the highest state of incubation to positions at the lowermost end of the row. This is accomplished by removing those trays near the 20 bottom in which the eggs are about to be hatched, lowering the entire series of trays and adding at the top of the row other trays of eggs.

The object of the invention is to provide 25 an improved mounting for the trays, such that the trays may be quickly and readily removed from one location in the row and installed in another position, or returned to the same position.

30 In the accompanying drawings:

Fig. 1 is a perspective view of several trays of a series and their mounting and connecting devices.

Fig. 2 is an end view of a pair of trays 35 showing the hangers and connecting devices.

Fig. 3 is a side view of the parts shown in Fig. 3.

Fig. 4 is a view of the opposite end of 40 one of the trays from that shown in Fig. 2.

Referring to the drawings, 1 and 2 represent the upper portions of two endless chains, which pass about sprocket wheels 3 at the ends of a transverse shaft 4. These 45 chains support the egg trays 5, which are of the usual construction, and provision is made for revolving the sprocket wheels 3 to lower the trays through a worm gear 7, connected to the shaft 4, worm 8, mounted in a suitably supported bracket 9 and crank 50 shaft 10, connected to the shaft 11 of the worm by joint 12.

The manner of hanging the trays on the chains is as follows: Secured to one end of each of the trays is a hanger consisting of 55 a flat metallic plate 13, secured to the tray

by bolts 14, and provided with an offset inner end 15, having a slot 16 which enters from the lower edge thereof, the slot being provided with a flaring mouth as shown. The opposite end of each tray has a similarly formed hanger, with the exception that the hanger 17 is shorter, but having the same offset portion 18 and slot 19. The slots 16 and 19 are located centrally with respect to the width of the tray and receive 60 links of the chains 1 and 2, whereby each tray is pivotally supported by central pivots to prevent tilting.

In order that the trays may be simultaneously tilted, I provide for connecting 65 them together, and also permit trays being removed from or added to the series of trays at any time desired. Pivoted at one end of each tray, preferably by the outermost bolt 14, is a link or connector 20 preferably of 70 flat sheet metal, the pivotal point being at the lower end of the link and such that the link is capable of swinging laterally. The inside edge of the link has a notch 21 to receive the bolt 14 of the next succeeding 75 higher tray so that the link or connector may be clamped between the hanger strip 13 and the lower end of the link 20 of the higher tray. A keeper 22 on each link is 80 slipped over the overlapping portion of the 85 companion link to prevent sidewise displacement of the links.

The operation of the device is as follows: 90 With the trays all connected by the links 20 as described, the entire series of trays may 95 be simultaneously tilted by grasping one of the trays and applying sufficient pressure to swing the entire series of trays about their pivotal points on the chains. Any suitable means (not shown) may be used 95 for holding the trays in tilted position. When it is desired to remove the lower trays, the same may be readily accomplished by slipping the keepers from the overlapping 100 portions of the links, swinging the links to the dotted line position of Fig. 2, and lifting the trays from the chains. The balance of the trays will then be lowered in the manner described to the extent of the 105 trays removed, and new trays replaced at the top of the row.

Having thus described my invention, I claim:

1. In a device of the character described, 110 a series of trays arranged in a vertical row,

- a pair of endless chains arranged respectively at the ends of said trays, a hanger on the end of each tray, each hanger being spaced from the tray sufficiently to permit the chain to straddle the hanger and having a notch arranged midway the width of the trays, said notches being adapted to engage the links of the chains to pivotally suspend the said trays, and means to move the chains to lower the trays.
2. In a device of the character described, a series of trays arranged in a vertical row, a pair of endless chains arranged, respectively, at the ends of said trays, a hanger having an offset notched portion arranged midway the width of the tray at each end of said tray, said notched portions being arranged to engage links of the chains to pivotally suspend the trays, a link pivoted to each tray, each arranged to overlap the link of an adjacent tray, and means for detachably connecting each link to an adjacent tray and to the link of each adjacent tray.
3. The combination of a plurality of trays, a flexible supporting member adjacent the ends of the trays, means for pivotally mounting each tray upon said supporting member, each tray being independently mounted upon the supporting member and independently removable therefrom, connectors for the trays, detachable means for securing connectors together whereby the trays are capable of being swung upon their pivots in unison as long as the connectors are secured together by the detachable means, and when said means are detached a tray can be removed without disturbing the other trays.
4. The combination of a plurality of trays, a plurality of flexible supporting members, one member being adjacent each end of the trays, means for operating said flexible supporting members in unison whereby the trays will be elevated and lowered simultaneously, means for pivotally mounting each tray upon said supporting members, the trays being independently mounted upon a longitudinal axis whereby same are capable of being tilted upon said axis in various angular relations, connectors for the trays, detachable means for securing the connectors together whereby the trays can be swung in unison, and when detached means are removed any tray can be removed without disturbing the other trays.

In testimony whereof, I have hereunto set my hand this 5th day of September, 1922.

SAMUEL B. SMITH.
